CLAIM

The ornamental design for a portable loudspeaker, as shown and described.

DESCRIPTION

FIG. 1 is a front view of the portable loudspeaker;
 FIG. 2 is a left side view of the portable loudspeaker;
 FIG. 3 is a rear view of the portable loudspeaker;
 FIG. 4 is a right side view of the portable loudspeaker;
 FIG. 5 is a bottom view of the portable loudspeaker;
 FIG. 6 is a top view of the portable loudspeaker;
 FIG. 7 is a rear top left perspective view of the portable loudspeaker; and,
 FIG. 8 is a left top front perspective view of the portable loudspeaker.
